Fig. 2.

A technical line drawing showing a long, thin metal strip with a wavy, undulating pattern. The strip is being bent into a U-shape, with a sharp corner at the bottom left. The strip is held in place by several clamps or supports, indicated by small circles with numbers 7, 12, 13, and 14. The ends of the strip are straight and extend to the right. The entire assembly is set against a background of a rectangular frame with diagonal cross-hatching.

BOILER CONSTRUCTION

Percy Jackson, Louisville, Ky., assignor to Henry
Vogt Machine Co., Louisville, Ky., a corpora-
tion of Kentucky

Application August 5, 1935, Serial No. 34,825

7 Claims. (Cl. 122—512)

This invention relates to improvements in boiler construction.

It has for its general object the provision of a boiler having front and rear tube supporting heads so constructed as to be self-supporting without necessitating the employment of the customary internal bracing members either above or below the tube sheets. The elimination of such braces avoids the presence of obstructions in the 10 water and steam spaces of the boiler and makes these spaces much more accessible for cleaning.

Another object of the invention is to provide front and rear heads, the tube sheet portions of which are flat and parallel whereby all the tubes 15 are of the same length. This is an obvious advantage to the boiler manufacturer from the standpoint of cheapness and ease of manufacture, and all of the tubes are subject to the same longitudinal expansion and contraction under varying heat conditions, being thus relieved from differential strains. Furthermore, the fact that the 20 tube sheet portions of the heads are flat and perpendicular to the tubes requires only that the tube sheets being perforated for receiving the 25 tube ends and dispenses with the expensive necessity of providing seats in the tube sheets for the ends of the tubes.

Another object of the invention is the provision of a boiler head of general dished shape having 30 a peripheral portion of spherical contour, a flat tube sheet area merging laterally directly into said spherical peripheral portion, the peripheral portion being extended to meet and merge with the lower boundary of the tube sheet portion, 35 excepting where modified as will appear, to provide a manhole, the vertical geometrical elements of the underlying spherical portion being rotund and constituting said underlying portion an efficient and adequate compression member for 40 supporting the tube sheets, the head being formed with an upper portion intermediate the spherical periphery and the upper boundary of the tube sheet, merging into the latter and into the contour of the spherical peripheral portion above it, 45 said upper intermediate portion being transversely very slightly curved so that it may be correctly described as being substantially flat, and having the curvature of those geometrical elements which lie in vertical planes, approximately 50 flat, making the upper intermediate portion as an optimum tension member for suspending the tube sheets and the weight of the tubes.

Still another object of the invention is the provision of a manhole in the boiler head beneath 55 the tube sheet portion formed in a reentrant

spherical depression in the outwardly convex lower portion of said head, the spherical contour of the boiler head in said depression affording the best shape for resisting deformation or collapse adjacent the edge of said manhole. 5

Still another object of the invention is to provide a boiler having dished heads, the peripheral margins of which merge smoothly with the cylindrical walls of said boiler.

Another object of the invention is to provide 10 a boiler with heads of the type described joined thereto by welding whereby a smooth surface is provided on the inside of the boiler to facilitate cleaning.

Other objects of the invention will appear as 15 the following description of preferred and practical embodiments thereof proceeds.

In the drawings which accompany and form a part of the following specification and throughout the several figures of which the same characters of reference have been employed to designate identical parts: 20

Figure 1 is a perspective view of a boiler illustrating a head embodying the principles of the 25 present invention;

Figure 2 is an end view of the same;

Figure 3 is a longitudinal section through the boiler showing both heads, the intermediate part being broken away;

Figures 4, 5, 6 and 7 are vertical sections taken 30 along corresponding section lines indicated in Figure 1;

Figure 8 is a horizontal section taken along the line 8—8 of Figure 2; and

Figure 9 is a section taken along the line 9—9 35 of Figure 2.

Referring now in detail to the several figures the numeral 1 represents a boiler which is here shown as being cylindrical having at the opposite ends heads 2 and 3, it being understood that 40 since the invention concerns itself primarily with the construction of the head, it is immaterial whether both heads of the boiler be alike or whether only one head embody the present inventive concept providing, in those concepts of 45 the invention which envision the advantages of having the tubes of equal length, that the opposite end of the boiler provide a flat tube sheet parallel with the tube sheet portion of the head which embodies the features of the present invention. 50

The head 2 is of general dished shape, outwardly convex and having its peripheral margin 4 preferably merging smoothly with the cylindrical wall of the boiler and being preferably butt- 55

welded thereto as at 5 to provide a smooth interior surface for the boiler shell. The peripheral curvature of the head adjacent the margin 4 is spherical as indicated at 6 and 7. The vertical sections illustrated in Figures 4, 5, 6 and 7 show that at the lower part of the head the spherical portion 7 extends outwardly and upwardly merging into the flat tube sheet portion 8, the latter being preferably, although not necessarily, in a vertical plane. The tube sheet portion 8 as will be observed particularly in Figure 2 extends preferably from a point above the horizontal diameter of the head to a point a greater distance below said horizontal diameter, defining a steam chamber 9 in the upper part of the boiler. The tube sheet portion being flat, it is merely necessary to perforate it for the reception of the tube 10, the latter intersecting it perpendicularly and being preferably welded thereto. It is not necessary to form the tube sheet portion with depressions or seats for fairly receiving the tube ends as would be required providing the tubes met the tube sheet portion in any other than a perpendicular relation. Since it is contemplated that the opposite end of the boiler will be provided either with a similar head or with a head providing a flat tube sheet parallel to the tube sheet 8, the tubes 10 will all be of the same degree of expansion or contraction under equal heat conditions so that no differential strain is put upon the tubes or upon the boiler head itself. The vertical geometrical elements of the underlying spherical portion 7 are of the very best shape to constitute the underlying spherical portion a compression member for upholding the weight of the tube sheet portions and tubes themselves.

The portion 11 of the boiler head immediately above the tube sheet portion 8 is very slightly curved transversely so that it may be said to be substantially flat, as is indicated in Figure 1 and Figures 4 to 7, inclusive, and the geometrical elements of said portion which lie in vertical planes are of such flat curvature as to be approximately rectilinear, constituting the portion 11 a tension member of optimum shape to suspend and sustain the weight of the tube sheet portions and tubes.

A manhole 12 is provided in the spherical portion of the head which underlies the tube sheet portion, said manhole being formed in a reentrant spherical depression 13 in the wall of said boiler head which spherical depression has the best possible shape to prevent distortion or collapse under the pressure generated within the boiler. Consequently, the edge 14 of the manhole which is a source of weakness in most boiler heads and has to be internally braced is thus made adequately strong and self-sustaining.

By the above construction a boiler head is provided which is self-supporting against thermal as well as hydrostatic or fluid pressure strains, thus enabling the manufacturer to dispense with the customary internal bracing, not only making an efficient and stronger boiler, but leaving the water and steam spaces free from obstructions so that it can be easily and completely cleaned through the access afforded by the manhole 12.

While I have in the above description defined what I believe to be a preferred and practical embodiment of the invention, it will be understood that the specific details of construction as shown and described are merely by way of example and not to be construed as limiting the scope of the invention as defined in the appended claims.

75 What I claim is:

1. Boiler comprising a shell having front and rear heads at least one of the heads being dished and having a flat tube sheet portion and a spherical marginal portion, the flat tube sheet portion merging into the spherical marginal portion laterally and below, said head having an intermediate portion above said tube sheet portion between the latter and the upper spherical marginal portion, said intermediate portion being substantially flat in a transverse direction and of approximately flat curvature in vertical planes said substantially flat portion being inclined at an acute angle to the plane of the tube sheet for tensionally supporting the weight of said tube sheet portion and tubes, the opposite head having a flat tube sheet parallel to the tube sheet portion of the other head, and tubes of equal length bridging the tube sheets.

2. Boiler comprising a curved shell having front and rear heads, at least one of the heads being dished and having a flat tube sheet portion and spherical marginal portion, the flat tube sheet portion merging into the spherical marginal portion laterally and below, said head having an intermediate portion above said tube sheet portion and between the latter and the upper spherical marginal portion, said intermediate portion being substantially flat in a transverse direction and of approximately flat curvature in vertical planes said substantially flat portion being inclined at an acute angle to the plane of the tube sheet for tensionally supporting the tube sheet portion and weight of the tubes, the opposite head having a flat tube sheet parallel to the tube sheet portion of the other head, and tubes of equal length bridging the tube sheets, the marginal portion of said head conforming to the curvature of said shell and registering with the end edges of said shell.

3. Boiler comprising a curved shell having front and rear heads, at least one of the heads being dished and having a flat tube sheet portion and spherical marginal portions, the flat tube sheet portion merging into the spherical marginal portion laterally and below, said head having an intermediate portion above said tube sheet portion and between the latter and the upper spherical marginal portion, said intermediate portion being substantially flat in a transverse direction and of approximately flat curvature in vertical planes said substantially flat portion being inclined at an acute angle to the plane of the tube sheet for tensionally supporting the tube sheet portion and weight of the tubes, the opposite head having a flat tube sheet parallel to the tube sheet portion of the other head, and tubes of equal length bridging the tube sheets, the marginal portion of said head conforming to the curvature of said shell and registering with the end edges of said shell, said head being welded to said shell and said tubes being welded to said tube sheet portion.

4. Boiler head comprising a dished member having a flat tube sheet portion and a spherical marginal portion, the flat tube sheet portion merging into the spherical marginal portion both laterally and below, said head having an intermediate portion above said tube sheet portion, between the latter and the upper spherical marginal portion, said intermediate portion being substantially flat in a transverse direction and of approximately flat curvature in vertical planes said substantially flat portion being inclined at an acute angle to the plane of the tube sheet for tensionally supporting said tube sheet portion.

5. Boiler head comprising a dished member having a flat tube sheet portion and a spherical marginal portion, the flat tube sheet portion merging into the spherical marginal portion both laterally and below, said head having an intermediate portion above said tube sheet portion between the latter and the upper spherical marginal portion, said intermediate portion being substantially flat in a transverse direction and of approximately flat curvature in vertical planes said substantially flat portion being inclined at an acute angle to the plane of the tube sheet, for tensionally supporting said tube sheet portion, said head below said tube sheet portion being provided with a reentrant spherical depression bounding a manhead opening.
6. Boiler head comprising a dished member having a flat tube sheet portion and spherical marginal portions, the flat tube sheet portion

merging into the spherical marginal portion laterally and below, the peripheral edge portion of said head being cylindrical, the geometrical cylindrical elements of which edge portion being perpendicular to said tube sheet portion, said head having an intermediate portion above said tube sheet portion and between the latter and the upper spherical marginal portion, said intermediate portion being substantially flat in a transverse direction and of approximately flat curvature in vertical planes said substantially flat portion being inclined at an acute angle to the plane of the tube sheet for tensionally supporting said tube sheet portion.

7. Boiler head as claimed in claim 6, the cylindrical peripheral edge portion being of progressively increasing length from the top to the bottom of said head.

PERCY JACKSON.
